CLAIM

The ornamental design for a control console for electronic security system, as shown and described.

DESCRIPTION

FIG. 1 is a front perspective view of a control console for electronic security system, showing our new design; FIG. 2 is a front elevational view thereof on a reduced scale relative to FIG. 1;

FIG. 3 is a left side elevational view thereof to the same scale as FIG. 2, with the right side being a mirror image thereof;

FIG. 4 is a top plan view thereof to the same scale as FIGS. 2 and 3;

FIG. 5 is a rear elevational view thereof reduced in scale relative to FIGS. 2-4; and

FIG. 6 is a bottom plan view thereof to the same scale as FIG. 5.

FIG. 1

FIG. 2**FIG. 3****FIG. 5****FIG. 6****FIG. 4**
